United States Patent Office

Des. 191,788
Patented Nov. 21, 1961

191,788

AUDIO-VISUAL INSTRUCTION APPARATUS

Charles J. Beggy, 432 Calle de Felipe, Torrance, Calif.

Filed Apr. 26, 1961, Ser. No. 64,904

Term of patent 14 years

(Cl. D25—1)

FIG. 1 is a perspective view of an audio-visual instruction apparatus, showing my new design;

FIG. 2 is a front elevational view; and

FIG. 3 is a side elevational view thereof.

The dominant features of my design reside in the portions shown in full lines.

I claim:

The ornamental design for an audio-visual instruction apparatus, as shown and described.
